(57) **CLAIM**

The ornamental design for a component of a constructor set, as shown and described.

DESCRIPTION

FIG. 1 is a top perspective view of a component of a constructor set showing the new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a top perspective view thereof in use with other components of a constructor set; and,

FIG. 9 is an alternate configuration thereof wherein the ends of the component are separated and the component is filed flat.

The portions of the design shown in broken lines in FIG. 8 show unclaimed subject matter. The broken lines shown in FIG. 9 are claimed and show the creases that form the corners in the primary configuration.
